UNITED STATES PATENT OFFICE.

JOHN DEBNAR, OF BLAIREVILLE, PENNSYLVANIA.

DEVICE FOR FEEDING MATERIALS INTO GLASS FURNACES.

Application filed February 24, 1926. Serial No. 90,806.

This invention relates to certain new and useful improvements in devices for feeding materials into glass furnaces and has for its primary object to provide a portable carriage embodying a multiple hopper construction with the carriage movable across a battery of furnace door openings with the device constructed in a manner to permit operation thereof and the feeding of a battery of furnaces by a single operator.

Another object of the invention is to provide a device for feeding materials into glass furnaces in the form of a portable carriage wherein the carriage is provided with a plurality of separate hoppers with an independently operable gate valve for each hopper with all of the hoppers selectively operated by a single person and further embodying novel operating devices for the gate valves.

A still further object of the invention is to provide a device of the character above set forth wherein a ladle or conveying bucket having a universal connection with a turn-table construction is capable of being disposed beneath the outlet mouth of the spaced hoppers to receive material therefrom for discharge or delivery into the glass furnace.

With the above and other objects in view that will become apparent as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a front elevational view of a device for feeding materials into a glass furnace showing the separate hoppers, the gate valves for the outlet mouths thereof and the roller carriage supporting the hopper.

Figure 2 is a top plan view of the device showing the front wall of the glass furnace in section and with the delivery ladle for the material projected through one of the furnace door openings.

Figure 3 is a vertical longitudinal sectional view taken on line 3-3 of Fig. 2 showing the separate hoppers and the turn-table construction for supporting the feeding ladle.

Figure 4 is a vertical cross-sectional view

taken on line 4-4 of Fig. 1 showing the operating devices for the sliding gate valve of an end hopper,

Figure 5 is a detail sectional view taken on line 5-5 of Fig. 1,

Figure 6 is a detail sectional view taken on line 6-6 of Fig. 1, and

Figure 7 is a plan view of an operating rod for the middle hopper valves and furnace doors.

The device for feeding the material into the glass furnace is in the form of a carriage mounted upon track rails 1 that are supported upon the flooring or base 2 forwardly of and parallel with the front wall 3 of a battery of furnaces that have entrance openings 4 in said front walls as clearly shown in Fig. 4, the openings 4 in the front walls of the furnaces being closed by the doors 5 shown in Fig. 3.

As shown in Fig. 3, the carriage embodies a base structure including longitudinal side bars 6 and end cross bars 7 supporting a platform 8, bolsters 9 depending therefrom supporting cross axles 10 that carry track wheels 11 upon the opposite ends thereof as shown in Fig. 4. Corner posts 12 project perpendicularly from the platform 8 and support a rectangular frame at their upper ends that comprises side bars 13 and end bars 14, the rectangular frame structure providing a support for the multiple hopper arrangement disposed above the platform 8. The upper rectangular frame is braced by the diagonal bars 15.

The hopper being supported upon and suitably secured to the upper rectangular frame embodies upper downwardly converging side walls 16 and downwardly converging end walls 17 having a pair of spaced transverse partition bars 18 and 19 disposed above the rectangular frame. The transverse partition bar 18 and the adjacent end wall 17 provides one hopper embodying downwardly converging bottom wall sections 20 and 21 with an outlet opening 22 at the lower end of the bottom wall 21 that is closed by a sliding gate valve 23. The hopper formed between the transverse partition wall 19 and the adjacent end wall 17 is of similar construction and the opening 22 in the wall 21 thereof is likewise closed by a sliding gate valve 23. The middle compartment between the transverse partition walls 18 and 19 embodies downwardly converging walls 24 and 25 with a

centrally positioned inverted V-shaped partition 26 dividing the central compartment into side compartments with an outlet opening 27 in each of the side compartments at the lower ends of the hopper wall 25 that are closed by sliding gate valves 28 as shown in Fig. 1. The outlet openings for the intermediate hoppers are located at one side of the carriage while the outlet openings for the end hoppers are disposed intermediate the opposite sides of the carriage as shown in Figs. 1 and 2. The several hoppers are adapted to contain material to be sent to the furnace for the manufacture of glass, such as sand, soda ash, lime and cullet or the like.

As shown in Fig. 1, the sliding gate valves 28 for the intermediate hoppers have guides 29 associated with the opposite side edges thereof and the operating means for the gate valves 28 include the provision of a bell crank lever 30 pivoted to the bottom wall sections 25 with link connections 31 between the end of one leg of the bell crank lever 25 and the upper end of the gate valve. The other leg of the bell crank lever is provided with a notch 32 to receive the hook end 33 of the operating rod 34 shown in Fig. 7 that may also be employed for opening the furnace doors 5.

The operating means for the gate valves 23 closing the outlet opening 22 of the end hoppers is shown more clearly in Figs. 1, 4 and 5 and include the bell crank lever 35 pivotally supported upon the bottom wall section 21 of the end hopper and having a link connection 36 with the upper end of the gate valve 23. A bell crank lever 37 pivotally supported beneath one of the upper side bars 13 of the upper rectangular frame has the free end of one of its legs pivotally attached as at 38 to a link 39, the other end of which is pivotally connected as at 40 to the other leg of the bell crank 35. A forked bracket 41 fixed to the side bar 13 above the bell crank lever 37 has an arm 42 pivotally mounted at one end between the outer forked end of said bracket while an operating lever 43 is pivoted at one end to the outer free end of the arm 42. A link 44 extends between the outer leg of the bell crank lever 37 and the operating lever 43 and when said lever 43 is shifted, movement is transmitted to the bell crank levers 37 and 35 for raising and lowering the sliding gate valve 23. In view of the relative positions of the pivot points for the arm 42 and the link 44, said arm and link with the operating handle 43 carried thereby may be shifted to a position adjacent the carriage when the device is out of use. The operating means for each of the sliding gate valves 23 associated with the end hoppers is identical and repetition of description is thought unnecessary.

The device for delivering the materials to the furnace includes a ladle supported upon an arm and turn-table construction which permits the ladle to be disposed beneath each of the outlet openings of the hoppers 70 and to be projected through the door openings 4 in the glass furnace. This construction embodies supporting legs or standards 45 shown more clearly in Figs. 1 and 3 having a disk head 46 upon which a rotatable turn-table 47 is supported with ball bearings 48 interposed therebetween, a central shaft 48 extending thru the disk 46 and turn-table 47. A horizontal arm 49 journaled on the shaft 48 and fixed to the turn-table 47 has a depending counterbalancing weight 50 at one end thereof, while the other end of the arm 49 is provided with a universal mounting for the ladle handle. A block 51 carries a depending stub shaft 52 85 journaled in the outer end of the arm 49, the block carrying a pair of upwardly directed side arms 53 in the upper ends of which side pins 54 carried by a ring 55 are journaled. The bucket ladle 56 is carried by a relatively long handle 57 that is rotatably mounted in the ring 55 against longitudinal movement therein. The ladle 56 is so disposed relative to the bearing for the handle 57 so that when the arm 49 is shifted upon the turn-table by manipulating the handle 57, the ladle may be disposed beneath any one of the outlets for the hoppers.

From the above detail description of the invention, it is believed that the construction and operation thereof will at once be apparent, it being noted that the carriage is movable over the track 1 forwardly of a battery of glass furnaces while a single person can manipulate the ladle 56 to dispose the same beneath the desired hopper and operate the sliding gate valve of the chosen hopper. The gate valves 23 for the end hoppers are operated by the lever 43 which causes shifting movement of the bell crank levers 37 and 35 for raising and lowering the gate valve while the gate valves 28 associated with the intermediate hoppers may be operated by the rod 34 shown in Fig. 7, which rod is also employed for opening and closing the furnace doors 5. With a device of this character wherein a single operator may charge the furnace with the desired material, a great saving in labor is effected as well as reducing the cost of manufacture.

While there is herein shown and described the preferred embodiment of the present invention, it is, nevertheless, to be understood that minor changes may be made therein without departing from the spirit and scope of the invention as claimed.

What is claimed is:—

1. In a device for feeding materials to

- glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, and independent means for operating each gate valve.
2. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, independent means for operating each gate valve, the discharge opening for the intermediate hoppers being disposed at one side of the carriage and the discharge openings for the end hoppers facing the intermediate hoppers, the operating means for the gate valves of the intermediate hoppers including a bell crank pivoted exteriorly of the hopper, a link connection between the bell crank lever and gate valve and means for operating the bell crank lever.
3. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, independent means for operating each gate valve, the operating means for the end hoppers, each including a bell crank lever pivoted exteriorly of the hopper, a link connection between the bell crank lever and gate valve, a bell crank lever mounted on the carriage, a rod connecting the two levers, and an operating handle positioned laterally of the carriage and attached to the second lever for operating the two levers and gate valve.
4. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, independent means for operating each gate valve, the operating means for the end hoppers, each including a bell crank lever pivoted exteriorly of the hopper, a link connection between the bell crank lever and gate valve, a bell crank lever mounted on the carriage, a rod connecting the two levers, an arm pivotally supported on the carriage, an operating handle pivoted to the outer end of the arm, and a rod connection between the operating handle and second bell crank for operating the two bell cranks and gate valve.
5. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, independent means for operating each gate valve, the operating means for the end hoppers, each including a bell crank lever pivoted exteriorly of the hopper, a link connection between the bell crank lever and gate valve, a bell crank lever mounted on the carriage, a rod connecting the two levers, an arm pivotally supported on the carriage, an operating handle pivoted to the outer end of the arm, a rod connection between the operating handle and second bell crank for operating the two bell cranks and gate valve.
6. In a device for feeding materials to glass furnaces, a portable carriage movable across the front walls of a battery of glass furnaces, a plurality of hoppers on the carriage, a ladle selectively positioned relative to the hoppers and movable through the furnace door openings, said ladle and its support including a turn-table on the carriage, a horizontal counterbalanced arm movable on the turn-table, and a handle for the ladle having a universal connection with the free end of the counterbalanced arm whereby the ladle may be selectively shifted to positions beneath the discharge openings of the hoppers.
7. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, said ladle and its support including a turn-table on the carriage, a horizontal counterbalanced arm movable on the turn-table, and a handle for the ladle having a universal connection with the free end of the counterbalanced arm whereby the ladle may be selectively shifted to positions beneath the discharge openings of the hoppers.
8. In a device for feeding materials to glass furnaces, a portable carriage movable across the front walls of a battery of glass furnaces, a plurality of hoppers on the carriage, a ladle selectively positioned relative to the hoppers and movable through

the furnace door openings, each hopper having a discharge opening at its lower end, a sliding gate valve for each opening, independent means for operating each gate valve, said ladle and its support including a turn-table on the carriage, a horizontal counterbalanced arm movable on the turn-table, and a handle for the ladle having a universal connection with the free end of the counterbalanced arm whereby the ladle may be selectively shifted to positions beneath the discharge openings of the hoppers.

9. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, independent means for operating each gate valve, the discharge opening for the intermediate hoppers being disposed at one side of the carriage and the discharge openings for the end hoppers facing the intermediate hoppers, the operating means for the gate valves of the intermediate hoppers including a bell crank pivoted exteriorly of the hopper, a link connection between the bell crank lever and gate valve, means for operating the bell crank lever, said ladle and its support including a turn-table on the carriage, a horizontal counterbalanced arm movable on the turn-table, and a handle for the ladle having a universal connection with the free end of the counterbalanced arm whereby the ladle may be selectively shifted to positions beneath the discharge openings of the hoppers.

10. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, independent means for operating each gate valve, the operating means for the end hoppers, each including a bell crank lever pivoted exteriorly of the hopper, a link connection between the bell crank lever and gate valve, a bell crank lever mounted on the carriage, a rod connecting the two levers, an operating handle positioned laterally of the carriage and attached to the second lever for operating the two levers and gate valve, said ladle and its support including a turn-table on the carriage, a horizontal counterbalanced arm movable on the turn-table, and a handle for the ladle having a universal connection with the free end of the counterbalanced arm whereby the ladle may be selectively shifted to positions beneath the discharge openings of the hoppers.

shifted to positions beneath the discharge openings of the hoppers.

11. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, independent means for operating each gate valve, the operating means for the end hoppers, each including a bell crank lever pivoted exteriorly of the hopper, a link connection between the bell crank lever and gate valve, a bell crank lever mounted on the carriage, a rod connecting the two levers, an arm pivotally supported on the carriage, an operating handle pivoted to the outer end of the arm, a rod connection between the operating handle and second bell crank for operating the two bell cranks and gate valve, said ladle and its support including a turn-table on the carriage, a horizontal counterbalanced arm movable on the turn-table, and a handle for the ladle having a universal connection with the free end of the counterbalanced arm whereby the ladle may be selectively shifted to positions beneath the discharge openings of the hoppers.

12. In a device for feeding materials to glass furnaces, a portable carriage movable across the front walls of a battery of glass furnaces, a plurality of hoppers on the carriage, a ladle selectively positioned relative to the hoppers and movable through the furnace door openings, each hopper having a discharge opening at its lower end, a sliding gate valve for each opening, independent means for operating each gate valve, the operating means for the end hoppers, each including a bell crank lever pivoted exteriorly of the hopper, a link connection between the bell crank lever and gate valve, a bell crank lever mounted on the carriage, a rod connecting the two levers, an arm pivotally supported on the carriage, an operating handle pivoted to the outer end of the arm, a rod connection between the operating handle and second bell crank for operating the two bell cranks and gate valve, said arm and rod being pivotally movable toward and away from the carriage, said ladle and its support including a turn-table on the carriage, a horizontal counterbalanced arm movable on the turn-table, and a handle for the ladle having a universal connection with the free end of the counterbalanced arm whereby the ladle may be selectively shifted to positions beneath the discharge openings of the hoppers.

In testimony whereof I affix my signature.

JOHN DEBNAR.
